SAND TRAP AND FILTER FOR OIL WELLS

Stephen J. Thomas, Long Beach, Calif.

Application January 22, 1940, Serial No. 315,070

9 Claims. (Cl. 166—5)

My invention relates to new and useful improvements in oil well construction.

An important object of my invention is the provision in an oil well construction of a sand trap adapted to be disposed below the oil bearing stratum and within the outer casing of the well to receive the sand and other residuum carried into the casing by the natural flow of the oil.

Another object of my invention is to associate the sand trap with the casing in a manner whereby the same may be easily and expeditiously removed from the well and the detritus emptied therefrom.

Still another object of my invention is the provision of an oil well construction of the above-mentioned character wherein the flow line pipe is adjustable to permit the open lower end thereof to be positioned slightly above the detritus in the trap at all times.

Yet another object of my invention is to provide an oil well construction of the above-mentioned character wherein it will only be necessary to draw a relatively short section of the casing together with the sand trap in order to effect a complete and efficient cleaning of the well and wherein no oil will remain in the casing section, and such quantities of oil as remain in the trap may be easily and expeditiously emptied therefrom when the same is drawn to the surface.

A further object of my invention is the provision in an oil well of a sand trap that may be easily applied to a conventional oil well construction and that is efficient and efficacious in the performance of its duties.

A still further object of my invention is to provide an oil well construction that comprises telescoping tubular sections uniquely associated to permit certain of the sections to be withdrawn from the well independently of the other sections and wherein the length of each of the sections is such as to require but a minimum length of section to be withdrawn in the practice of the invention.

Other objects and advantages of my invention, will be apparent during the course of the following description.

In the drawings, forming a part of this specification, and wherein like numerals are employed to designate like parts throughout the same,

Figure 1 is a side elevation, showing parts broken away, of the upper section of an oil well construction embodying my invention.

Figure 1A is a longitudinal sectional view of another section of my improved oil well construc-

tion subjacent to the section illustrated in Figure 1.

Figure 1b is a longitudinal sectional view of still another section of my improved oil well construction subjacent to the section illustrated in Figure 1a.

Figure 1c is a longitudinal sectional view of yet another section of my improved oil well construction subjacent to the section illustrated in Figure 1b, and

Figure 2 is an exploded perspective view of an anchor or stop element embodying a part of my invention.

In the accompanying drawings, wherein for the purpose of illustration, is shown a preferred embodiment of my invention, the numeral 10 designates a conventional Christmas tree or manifold valve construction disposed at the surface of the ground above the well and surmounted by the usual plug or cap 11. A discharge branch 40 extends laterally of the Christmas tree, a control valve 41 is coupled therewith in the conventional manner to regulate the flow of oil therethrough and a pressure gauge 42 is connected to and communicative with the line 40 to register the hydrostatic pressure of the oil flowing therethrough. An inlet conduit 82 is connected to the Christmas tree and includes a control valve 83 and pressure gauge 84. The valve 83 controls the flow of fluid through the pipe into the manifold valve and the gauge 84 registers the pressure of the same. The base of the valve 10 is formed with an annular flange 12 to which the annular flange 13, formed at the upper end of the casing 14, is secured by means of the bolts 15. The casing 14 extends downwardly to a point slightly above the upper surface of an oil bearing stratum and the relative short hanger section 16 is attached thereto in longitudinal alignment therewith by the coupling 17. The upper end 18 of the hanger section is of the same diameter as the casing 14 and the lower end thereof is tapered inwardly as at 19 and terminates in a cylindrical skirt portion 20.

The foraminated casing 21 is of lesser diameter than the casing 14 and is adapted to be lowered therethrough. The upper end of the casing is screw-threaded, as at 22, to engage the internally screw-threaded lower end 23 of the companion hanger section 24. The middle portion of the hanger section 24 is flared outwardly as at 26, and the upper end thereof is of substantially cylindrical formation and of slightly greater diameter than the flared portion 26 to define an external annular bead 26' but of lesser diameter than

the internal bore of the casing 14. The inwardly tapered portion 26 of the male hanger section is provided with a peripheral groove 27 adapted to receive the sealing ring 28 which bears against the seat formed by the inwardly tapered portion 19 of the hanger section 16 to form a fluid tight union between the hanger sections. The tapered portion of the hanger section 16 is formed with an internal annular seat 19' adapted to engage the bead 26' of the hanger section 24 to effectively support the said hanger and the tubular sections carried thereby.

The upper level of the oil bearing stratum is designated by the numeral 29 in Figure 1a, and the lower casing 30 is secured to the uppermost casing 21 in longitudinal alignment therewith by the coupling 31. The foraminated sections of the casings 21 and 30 extend through the oil bearing stratum, the lower level of which is designated by the numeral 32, and longitudinally aligning sections of as many of the foraminated casings as are necessary to traverse the stratum are held together by the couplings 31. The openings in the casings are preferably diamond-shaped and are spaced annularly therearound, as clearly shown in Figures 1a, 1b, and 1c.

The foraminated sections terminate at the bottom level 32 of the oil bearing stratum and the solid tubular casing 33 is secured thereto in longitudinal alignment therewith by the coupling 31. The casing 33 may be of any desired length, preferably extending for a considerable distance below the lower level of the oil stratum and has a female hanger section 34 secured to the lower end thereof by a coupling 31. The upper end 35 of the hanger section is of the same diameter as the casing 33 and tapers inwardly therebelow, as at 36, which portion terminates in a depending annular skirt 37.

The flow line pipe 38 is suspended from the plug 11 by means of the transverse pin 39 and extends through the sections of the casing and into the section 33 below the lower level 32 of the oil bearing stratum. The pipe is adapted to convey the oil to the surface of the ground and is therefore connected with the discharge pipe 40.

A foraminated liner section 43, of slightly lesser diameter than the foraminated casing 30, is disposed within the casing 30 and extends between the upper and lower levels of the oil bearing stratum. The apertures in the liner 43 are in the form of elongated slots, and are preferably larger than the apertures in the outer casing 30 to assure a free and unrestrained flow of oil therethrough. The foraminated liner section terminates at the lower level 32 of the stratum and a plain tubular section 44, comprising a sand trap, is connected thereto in longitudinal alignment therewith by the coupling 45. The lower end 46 of the plain liner 44 is similarly connected to the male hanger section 47 by a coupling 45. The hanger section is tapered inwardly as at 48 adjacent the lower end thereof and the tapered portion terminates in a cylindrical apron 49, the lower end of which is externally screw-threaded to receive the cap 50. The cap is formed with a central inlet stem 51 surmounted by a conical shaped cover provided with a plurality of radially disposed slots 53. The stem 51 is formed with a central bore 54 which affords communication with the sand trap through the cap 50.

The upper end of the foraminated liner 43 terminates at a point slightly below the upper level 29 of the oil bearing stratum and is externally screwthreaded to receive the lockhead 55.

The inner bore of the lockhead curves inwardly, as at 56, to define a substantially upper thick collar 57 disposed in abutting relation with the lower annular flange 58 of the gooseneck 59. The gooseneck preferably comprises companion shells or sections adapted to be applied at opposite sides of the flow line pipe and to be held together by bolts 59', or the like. The lower flange 58 of the gooseneck is provided with a plurality of spaced annular openings through which the bolts 60 are inserted to engage aligning openings in the collar 57 of the lockhead. An oil diverter 61 comprises a cap surmounting the upper end of the gooseneck and having a sliding fit with the flow line pipe. The oil diverter is also preferably made of split sections which permit the same to be easily applied to the pipe and, when assembled, prevent oil from flowing along the outer surface of the pipe and through the gooseneck 59.

Guards 62 are mounted at spaced intervals along the foraminous liner 43 and comprise spaced collars 63 and 64 fixedly associated with the liner and connected by a plurality of spaced outwardly bowed resilient webs 65. The webs 65 have a light frictional engagement with the inner periphery of the casing and hold the liner concentrically disposed therein.

An oil ring and scraper 66 is carried by the liner 43 adjacent the lower extremity thereof. The ring comprises an annular section 67 encircling the liner slightly below the lowermost openings; the section 67 having an outwardly flared upper portion 68 adapted to frictionally engage the inner wall of the outer casing 30. A collar 69 encircles the lower portion of the ring to hold the same fixedly attached to the liner.

Guards 70 are similarly disposed at spaced intervals along the flow line pipe 38 and similarly comprise spaced collars 71 and 72 fixedly associated with the pipe and integrally connected by a plurality of spaced outwardly bowed resilient webs 73 which engage the inner periphery of the liner 43 to hold the flow line pipe concentrically disposed therein.

An anchor or stop element 74 is carried by the flow line pipe a substantial distance below the gooseneck 59, which distance should correspond roughly to the length of the sand trap 44 for reasons hereinafter set forth. The anchor 74 comprises hemicylindrical companion shell sections 75 and 76 provided with registering axial grooves 77 and 78, respectively. Shell section 75 is provided with a plurality of tapped openings 79 adapted to register with the openings 80 in the shell section 76 and to receive the threaded ends of the bolts 81. The anchor is preferably constructed in sections to permit the same to be easily applied to the flow line pipe and to be easily adjusted thereon; and the bolts 81 may be tightened to move the sections toward each other and into close frictional engagement with the said pipe. A second stop or anchor 74 is similarly disposed a substantial distance above the gooseneck.

My invention is particularly adapted to prevent the well from being rendered inoperative by the accumulation of sand in the lower portion thereof. The outer casing 14 is first lowered into the well until the lower end thereof is positioned slightly above the upper level of the oil stratum. The lower end is then cemented and a hole drilled in the cement through which the slightly smaller casing 21 together with the foraminated sections 30 and sand trap 44 may be dropped. The sections 30 are lowered through the section 14 until

the male hanger section 24 seats on the inwardly tapered section 19 of the female hanger section 16, illustrated in Figure 1a. The liner sections 43 and 44 connected to the flow line pipe 38 are then lowered through the casing. The lower stop 74 will engage the bottom end of the gooseneck 59 to hold the liner sections suspended from the flow line pipe as the liners are lowered into the well and the resilient action of the guards 62 will guide the liner in its travel to prevent the casing from being damaged. The male hanger section 47 suspended from the lower end of the sand trap will seat on the inner face of the inwardly tapered portion 36 of the female hanger section 34, and thereafter the flow line pipe may be lowered to position the open end of the same slightly above the stem 51.

The stem 51 will permit any oil which has collected at the bottom of the casing 33 to flow into the sand trap, thus obviating the possibility of the oil preventing the trap from being lowered the desired distance. The stop 74 carried by the flow pipe above the gooseneck will engage the upper end of the gooseneck to force the liner and sand trap along the casing, if necessary.

The casing 14 may extend for several thousands of feet below the surface of the ground to the upper surface of a stratum of oil bearing sand. The length of the foraminated casing and liners will, of course, be governed by the depth of the stratum of sand and the sand trap may extend several hundred feet below the oil bearing sand.

The oil in the sand may flow through the diamond-shaped foraminations in the casings 21 and 30 and through the elongated slots in the foraminous liners 43. The oil rings and scrapers 66 disposed at spaced intervals along the foraminous lining 43, by reason of the frictional engagement thereof with the inner periphery of the casing, will collect the oil flowing down the inner wall of the casing and direct the same through the slots in the liner 43 and into the sand trap 44. The inflow of oil through the casing will carry slight quantities of sand therewith. As the oil flows through the liner and into the sand trap, the sand and other detritous will settle to the bottom of the trap and the oil will fill the portion of the trap above the sand. The adjustable feature of the flow line pipe which permits the same to move independently of the liner for a limited distance, permits the open lower end thereof to be spaced slightly above the accumulating sand in the sand trap at all times and to convey the oil to the surface by pressure or pumping methods.

The foraminations in the outer casing 30 are preferably diamond-shaped for the reason that the sand carried by the oil flowing therethrough will tend to collect and pack in the openings, thus preventing the free flow of oil therethrough. However, by using the diamond-shaped perforations the sand will not collect therein to such a marked degree due to the fact that the center or middle part of the diamond-shaped opening is wide and tapers to a point at both ends. This enables a deposit of sand collected therein to be broken away very easily and with a minimum amount of suction.

When the sand trap becomes full or substantially full and the flow line pipe has been elevated to a position where the lower stop 74 engages the bottom of the gooseneck 59, it will be necessary to pull the perforated lining 43, together with the sand trap, from the well and

during this operation water, oil or other fluid is pumped into the well through the inlet conduit 82 to maintain the oil and gas pressure of the well. The fluid need only to be pumped into the casing and it is not necessary that the same be pumped into the oil sand, thus making it unnecessary to disturb the oil sand structure. After the well is filled with oil, or other fluid, the liner and sand trap may be pulled to the surface by any suitable means and the sand and other detritous emptied from the trap and new sections substituted for old or worn ones. The operation of removing the liner and sand trap is easily accomplished within a very short time and the unit can be pulled up at any time for cleaning or inspection. The oil rings and scrapers 66 frictionally engage the inner bore of the casing and scrape and clean the surface of the same when the liners and sand trap are being drawn from the casing.

In the event that the flow line pipe 38 should break, an over-shot tool may be secured to the end of the drill pipe and lowered into engagement with the gooseneck. The lock of the tool may then be released to cause the same to engage with the gooseneck to permit the liner and sand trap to be drawn to the surface. After the trap has been thoroughly cleaned and any necessary portion thereof repaired, the liner and trap may be lowered into the well, the oil or water previously pumped into the well may be removed by a pumping or swabbing operation and pumping operations resumed.

It is to be understood that the form of my invention, herewith shown and described, is to be taken as a preferred example of the same, and that various changes in the size, shape and arrangement of parts may be resorted to without departing from the spirit of my invention, or scope of the appended claims.

Having thus described my invention, I claim:

1. In an oil well construction, a sand trap comprising an impervious tubular casing adapted to be disposed below the oil bearing strata; and an impervious tubular liner of lesser diameter than the casing disposed concentrically in the casing and being entirely enclosed thereby, the lower end of the said liner having a sealed engagement with but not connecting to the casing and having an open top to permit passage of a fluid therein and a perforate bottom to permit fluid in the casing to have access into the liner when the lower end of the same is lowered into engagement with the casing.

2. In an oil well construction, a sand trap comprising an impervious tubular casing adapted to be disposed below the oil bearing strata, an impervious tubular liner of lesser diameter than the casing disposed concentrically in the casing and being entirely enclosed thereby, the lower end of the said liner engaging but not connecting with the casing having an open top to permit passage of a fluid therein and a perforate bottom to permit fluid in the casing to have access into the liner when the lower end of the same is moved into engagement with the casing, and oil rings girdling the liner and engaging the contacted surface of the casing to form a fluid-tight union therewith.

3. In an oil well construction, a sand trap comprising an impervious tubular casing formed with a constricted lower end, an impervious tubular liner disposed concentrically within said casing for substantially its entire length and with the lower end thereof supported by but unconnected

with the constricted lower end of the casing and a flanged collar girdling the upper end of the liner and extending obliquely therefrom to wipingly engage the inner wall of the casing to prevent foreign particles from having access to the space between the liner and casing.

4. In an oil well construction, a foraminous tubular casing adapted to extend through an oil stratum and to terminate at its upper and lower levels, a plain tubular casing connected to the lower end of the first casing and adapted to extend a substantial distance below the oil stratum, a foraminous tubular liner coextensive with the first foraminous casing, and in circumferentially spaced relation therewith in a manner to be readily removable therefrom, and a plain tubular liner comprising a sand trap connected to the first liner and extending into the plain casing, the said last liner being supported by but not connected to the said plain casing in a manner to be removable with the said foraminous liner.

5. In an oil well construction, a foraminous tubular casing adapted to extend through an oil stratum and to terminate at its upper and lower levels, a plain tubular casing connected to the lower end of the first casing and extending a substantial distance below the oil stratum, a foraminous tubular liner coextensive with the first foraminous casing and in circumferentially spaced relation therewith whereby to be readily removable therefrom, a plain tubular liner having a closed bottom end and comprising a sand trap connected to the lower end of the first liner and extending into the plain casing, the last-mentioned liner being supported by but not connected to the plain casing whereby to be removable with the said foraminous liner, and a collar girdling the upper end of the plain liner and wipingly engaging the inner wall of the plain casing to direct solid particles entering the foraminations of the first casing into the said sand trap.

6. In an oil well construction, the combination of a foraminous tubular casing adapted to extend through an oil stratum and to terminate at its upper and lower levels, a foraminous liner concentrically disposed within and circumferentially spaced from said casing, an impervious casing connected to the lower end of the foraminated casing, an impervious liner connected to the lower end of the foraminated liner and extending into but not connecting with the impervious casing, an oil conduit concentrically disposed within said liners and being freely axially movable therein, a collar slidable on the oil conduit and fixedly connected to the upper end of the liner, and stop means fixedly carried by the oil conduit above and below the collar and being spaced apart a sufficient distance to permit the lower end of the conduit to travel the full length of the impervious liner, the said lower stop means being uniquely adjusted to engage the collar upon upward movement of the conduit to move the said liners upwardly therewith.

7. In an oil well construction, the combination of a foraminous tubular casing adapted to extend through an oil stratum and to terminate at its upper and lower levels, a foraminous liner con-

centrically disposed within and circumferentially spaced from said casing, an impervious casing connected to the lower end of the foraminated casing, an oil conduit concentrically disposed within said liner and being freely axially movable therein, a collar slidable on the oil conduit and connected to the upper end of the liner, a sand trap carried by and disposed below the liner and adapted to receive the lower end of the oil conduit, and a stop means fixed to the conduit above and below the collar and being spaced apart a sufficient distance to permit the lower end of the conduit to travel the full length of the said trap, the said lower stop means being uniquely adjusted to engage the collar during the upward movement of the conduit to elevate both the said liner and trap.

8. An oil well construction comprising an outer casing extending from the ground surface to a point substantially below the bottom level of an oil bearing strata, said casing being impervious except for a perforated section extending between the upper and lower levels of the strata; an inner liner freely axially movable within the casing and extending from the upper level of the strata to the lower end of the casing, the portion of the liner extending through the oil bearing strata being perforated and the portion thereof extending below the strata being impervious and comprising a sand trap; and a collar encircling the liner at the juncture of the perforated and impervious sections, the said collar having a peripheral wiping engagement with the inner periphery of the casing to direct foreign particles entering the perforated sections of the casing and liner into the said sand trap.

9. An oil well construction comprising an outer casing extending from the ground surface to a point substantially below the bottom level of an oil bearing strata, said casing being impervious except for a perforated section extending between the upper and lower levels of the strata; an inner liner freely axially movable within the casing and extending from the upper level of the strata to the lower end of the casing, the portion of the liner extending through the oil bearing strata being perforated and the portion thereof extending below the strata being impervious and comprising a sand trap; a collar encircling the liner at the juncture of the perforated and impervious sections, the said collar having a peripheral wiping engagement with the inner periphery of the casing to direct foreign particles entering the perforated sections of the casing and liner into the said sand trap; an oil conduit extending from the ground surface and through the liner; and coupling means connecting the oil conduit to the liner but permitting the conduit to have a limited independent axial movement within the liner sufficient to permit the lower end of the conduit to travel the entire length of the sand trap whereby positioning the conduit at the upper limit of its independent travel will render the coupling means operative and whereby further elevation of the conduit will move the liner axially within the said outer casing.

STEPHEN J. THOMAS.
